UNITED STATES PATENT OFFICE

LESLIE CHARLES JOHNSTON, OF SYDNEY, NEW SOUTH WALES, AUSTRALIA

INSECTPROOF SCREEN MEANS FOR WINDOWS OR DOORS

Application filed October 22, 1931, Serial No. 570,324, and in Australia October 27, 1930.

This invention relates to insect-proof screen means for windows or doors, and the object of the invention is to provide cheap, simple and effective means, whereby when a window or door is open insects such as flies or otherwise can not gain access to the interior of the enclosure through the window or door opening with which the said means are associated. The invention is applicable

10 either to sliding or to casement windows.

Fig. 1 is a perspective view of a window frame fitted with the screen means; Fig. 2 is a sectional elevation; Fig. 3 is an enlarged sectional detail; Fig. 4 is an enlarged detailed perspective view; Fig. 5 is an enlarged sectional plan on plane 5—5, Fig. 4; Fig. 6 is an elevation view of one of the vertical cambered members; Figs. 7 and 8 are sectional plans on lines 7—7 and 8—8, Fig. 6; Fig. 9 is a perspective view of a part of a screen framing of modified construction; Fig. 10 is an enlarged sectional view similar to Fig. 5, but showing a modified construction; Fig. 11 is a perspective view of a doorway fitted with a screen; and Fig. 12 is a sectional elevation thereof.

Referring to Figs. 1 to 8, a framing is provided which is preferably constructed of wood; said framing consists of a pair of vertically disposed cambered members 2 and a top horizontally disposed member 3. The member 3 carries a plurality of coil springs 4. To each of the springs 4 is fixed a horizontally disposed bar 5 to which is attached one end 30 of a sheet of gauze or like screen netting 6; the other end of the sheet 6 is connected to a roller 7. The screen 6 is extended between the cambered members 2, and its lateral sides are adapted to run on the cambered portions 40 of the members 2 when the roller 7 is moved upwardly or downwardly.

Each end of the roller 7 is provided with a fixed stub spindle 10, and each of said spindles is furnished with a bearing bracket 45 11, as well as with a spur pinion 12 fixed to the stub spindle 10. The roller 7 is fitted with a cover 14 which also serves to cover the spur pinions 12. Cover 14 is firmly secured to the bearing bracket 11 by screws 13.

50 The spur pinions 12 are adapted to mesh

with the cambered rack bars 16 which are secured to the cambered members 2 within recesses 17 therein. Each of the recesses 17 are slightly deepened on one side of each of the rack bars 16 whereby a vertical cambered groove or raceway 18 will be formed in said recesses. Within each of the raceways 18 is adapted to slide a flanged portion 19 located on each of the bearing brackets 11, whereby the spur pinions 12 are maintained in contact with the rack bars 16, and the gauze sheeting 6 is simultaneously firmly held in contact with the cambered faces 9 of the members 2.

Said cambered faces 9 are disposed slightly out of alignment with the cambered rack bars 16 at the upper ends of the cambered members 2 for the purpose of accommodating the roller 7 and thereby to maintain the gauze sheet 6 in close contact with the said cambered faces 9 (see Figs. 6, 7 and 8).

Although the screen has been shown as applied to a window it may also be applied to a door in a similar manner.

In operation, upon the framing consisting of the members 2 and 3 having been mounted on a window or door frame, the gauze or like screen 6 can be readily raised or lowered on the cambered portions of said framing about the window or door opening to allow full admission of air to an enclosure without entrance thereto of flies or other insects; in such operation, the spur pinions 12 engage with the rack bars 16 and the spring tension means 4 associated with the bar 3 enables the gauze or like screen 6 to be evenly rolled onto or unrolled from the roller 7 without leaving any space between such screen 6 and the cambered faces 9 of the members 2. If flies are not to be admitted through the window or door opening it will be understood that the screen sheeting 6 must always cover the window or door opening even though the window or door or part thereof may be open.

Referring to Figs. 9 and 10, wherein the top bar 5 is shown rigidly secured to the top member 24, in such construction the spring tensional means are directly associated with the roller 7 (see Fig. 10). The spindle 20 is loosely mounted in the roller 7 and the

bearings 11, and each end of the roller 7 is furnished with a cylindrical chamber 21 to accommodate a coil spring 22 one end of which is rigidly secured to the spindle 20 while the other end thereof is anchored to a 5 hooded cover 23 which is secured to the roller 7. The spur pinions 12 are fixed to the spindle 20.

The operation of raising or lowering of the screen will be as above described.

10 With reference to Figs. 11 and 12 wherein the screen means are shown as applied to a doorway, it will be understood that such construction of the screen may also be utilized on a window framing.

15 In such embodiment of the invention the construction of roller 7 with spindle 20 and appurtenant parts as shown in Fig. 10 are preferably used. To one of the vertical members 25 of the doorway is secured the bar 5 to which one end of the screen 6 is attached. The spur pinions 12 of the roller 7 mesh with horizontally disposed rack bars 16 which are affixed to the horizontally disposed cambered members 2. The upper cambered member 2 is fastened to the top cross member 26 of the doorway while the bottom member 2 may be secured to the flooring 27. Otherwise the cambered members 2 are constructed in similar manner to that shown in Fig. 2, and the operation of the said screen means are similar to that before described.

20 What I claim as my invention and desire to secure by Letters Patent is:—

35 1. Insect proof screen means for windows or doors comprising a framing associative with a window or door and which includes recessed cambered means carrying cambered rack bars within the recessed portion of said 40 cambered means, a roller to which one end of the screen sheeting is attached, means associated with the window or door to which the other end of the screen sheeting is attached, a spur pinion on each end of the roller adapted to mesh with the said rack bars, and spring tensioning means for said screen sheeting.

45 2. Insect proof screen means according to claim 1, in which tensioning means for the screen sheeting consist of a series of coil springs which are interposed between the screen sheeting and the means to which said other end of the screen sheeting is attached.

50 3. Insect proof screen means according to the preceding claim 1, in which the roller for the screen has associated therewith at opposite ends, stub axles for the spur pinions and recessed flanged bearings therefor, and the recesses in the cambered parts of the 55 framing are deepened on one side to allow the flanged portions of the said bearings to slide in said recesses to enable the spur pinions to be kept in contact with the cambered rack bars.

60 4. Insect proof screen means according to

the preceding claim 1, in which the rack bars are located in the recesses of the cambered means of the framing and the cambered faces of the latter means are disposed slightly out of alignment with the rack bars for the purpose of accommodating the varying diameter of the screen sheeting roller as the said sheeting is wound on said roller.

65 In testimony whereof I affix my signature.

LESLIE CHARLES JOHNSTON.
